MUFFLING DEVICE

William A. Morrison, Easton, Pa., assignor to
 Ingersoll-Rand Company, Jersey City, N. J., a
 corporation of New Jersey

Application April 6, 1937, Serial No. 135,221

4 Claims. (Cl. 121—35)

This invention relates to muffling devices, and more particularly to an exhaust muffling device for pneumatic tools of the percussive type.

One object of the invention is to effectively suppress the sound waves induced by the emission of the fluid from the motor and to transform the exhaust impulse into a substantially steady stream.

Another object is to equip the pneumatic tool with a simplified and effective muffling device which will not add materially to the weight of the tool and which may be readily and cheaply replaced.

Other objects will be in part obvious and in part pointed out hereinafter.

In the drawing accompanying this specification and in which similar reference numerals refer to similar parts:

Figure 1 is an elevation, in section, of a muffling device constructed in accordance with the practice of the invention and showing it applied to a pneumatic tool of the percussive type, the latter being partly broken away, and

Figures 2 and 3 are transverse views taken through Figure 1 on the lines 2—2 and 3—3, respectively.

Referring more particularly to the drawing, the muffling device, designated in general by 20, is shown applied to a fluid actuated percussive tool 21 comprising a cylinder 22 and front and back heads 23 and 24, respectively.

The interior of the cylinder constitutes a piston chamber 25 containing a hammer piston 26 which actuates a working implement 27 extending into the front head and controls a free exhaust port 28 for the piston chamber 25. The piston 26 is of the differential type and has a stem 28 which extends slidably through a bushing 29 in the front end of the piston chamber to strike against the working implement 27.

The pressure fluid employed for actuating the piston 26 may be distributed to the ends of the piston chamber 25 by suitable valve mechanism of which only the outer casing part 30 is shown.

The valve mechanism may, as illustrated, be arranged between the piston chamber and the back head 24 and be in communication with the ends of the piston chamber 25 through suitable ports and passages (not shown).

The muffler 20 constructed in accordance with the practice of the invention is in the form of a tubular member or sleeve 31 which surrounds the intermediate portion of the pneumatic tool comprising the cylinder 22 and the valve mechanism 30. The rearmost end 32 of the sleeve seats

against a shoulder 33 of the back head 24 and is centralized with respect to the back head by a projection 34 of the back head extending into the sleeve.

The sleeve 31 is of somewhat larger diameter than the casing parts which it surrounds and with which it cooperates to define a space or chamber 35 to receive the exhaust fluid issuing from the exhaust port 28. The forward portion 36 of the sleeve 31 is contracted to an approximate conformation with the shape of the adjacent portion of the rock drill casing, and extending into the front end of the sleeve 31 is a boss 37 carried by a ring 38 to which the front end of the sleeve may be permanently secured, as by welding.

The ring 38 seats against the rear end of the front head 23, in the assembled positions of the parts, and has a sliding fit on the periphery of the adjacent casing part.

Within the sleeve 31 are a series of partitions 39, 40 and 41, transversely arranged in the present instance, to divide the interior of the sleeve into a plurality of expansion chambers 42, 43 and 44. The chamber 44 constitutes the final expansion chamber and in the portion of the sleeve 31 defining it are a plurality of ports 45 to afford communication between the chamber 44 and the atmosphere.

The chamber 43 is the intermediate expansion chamber and that designated 35 constitutes the initial expansion chamber into which the pressure fluid is directly exhausted from the piston chamber 25. As a preferred arrangement, the partition 39 forming the upper bounding surface of the chamber 42 is disposed intermediate the exhaust port 28 and the valve mechanism 30 to prevent the exposure of the valve mechanism to the direct chilling influence of the expanded fluid flowing through the chamber 42. The partitions 39, 40 and 41 are in the form of annular plates affixed to the sleeve and of which the inner and outer surfaces abut the cylinder 22 and the sleeve 31, respectively.

To the end that maximum suppression of the sound waves may be obtained in each chamber the passages affording communication between the adjacent chambers are defined by conduits extending through the partitions and secured to the inner surface of the sleeve 31. A conduit 46 is accordingly arranged in the partitions 40 to extend from a point near the partition 39 to a point spaced from the partition 41 only a sufficient distance to permit the free egress of fluid from the conduit 46 into the chamber 43. Simi-

larly, a conduit 47 is arranged in the partitions 41 and extends from the upper portion of the chamber 43 into the chamber 44.

Owing to the arrangement of the conduits with respect to the expansion chambers the exhaust fluid is required to travel a path of maximum length possible with the structure illustrated and a maximum dampening effect is, therefore, obtained in each chamber.

As is well known, under certain climatic conditions the low temperature resulting upon expansion of the exhaust fluid causes the moisture entrained by the fluid to congeal and, in consequence the ice may accumulate within the muffler and seriously diminish the areas of the passages through which the fluid flows to the atmosphere. In order, therefore, to prevent an occurrence of this nature the expansion chamber 42 is provided with a flexible sheet 48, as for example rubber, to confront the exhaust port 28.

In order to assure an undulatory or flapping motion of the sheet 48 said sheet 48 is suspended from a rivet 49 fastened to the sleeve 31. A washer 50 is interposed between the sheet and the sleeve 31 to space the sheet a slight distance from the sleeve and thereby enable the sheet to be freely agitated and flexed by the exhaust fluid issuing from the exhaust port 28 to break up any ice that may form on the sheet.

In practice the present invention has been found to be a highly efficient device for suppressing the sound vibrations caused by the intermittent impulses of the exhaust fluid issuing from the piston chamber. During its passage through the sleeve the exhaust fluid passes through successive expansion zones and the impulses are evened out without causing an appreciable back pressure. The exhaust fluid, therefore, finally passes through the ports 45 as a substantially constant stream.

I claim:

1. In a muffling device, the combination of a pneumatic tool casing having a piston chamber and an exhaust port for the piston chamber, a sleeve around the casing to receive exhaust pressure fluid issuing from the exhaust port and having an outlet opening, transverse partitions in the sleeve to divide the interior of the sleeve into compartments, and a conduit extending into the outer ends of adjacent compartments for conveying fluid from one compartment to another. 10

2. In a muffling device, the combination of a pneumatic tool casing having a piston chamber and an exhaust port for the piston chamber, a sleeve around the casing to receive exhaust fluid 15 issuing from the exhaust port and having an outlet opening, partitions in the sleeve to divide the interior of the sleeve into compartments, and conduits in the partitions extending into the adjacent compartments to convey fluid from one 20 compartment to another.

3. In a muffling device, the combination of a pneumatic tool casing having a piston chamber and an exhaust for the piston chamber, a sleeve around the casing to receive the exhaust fluid 25 issuing from the exhaust port and having an outlet opening, and means agitated by the exhaust fluid to prevent the accumulation of ice within the sleeve.

4. In a muffling device, the combination of a 30 pneumatic tool casing having a piston chamber and an exhaust for the piston chamber, a sleeve around the casing to receive the exhaust fluid issuing from the exhaust port and having an outlet opening, and a flexible member in the sleeve 35 confronting the exhaust port and being agitated by the exhaust fluid to prevent the accumulation of ice within the sleeve.

WILLIAM A. MORRISON. 40
